SPACER MEMBER

Bryant L. Britt and Wilfred C. Potter, St. Johns, Mo., assignors to Wagner Electric Corporation, St. Louis, Mo., a corporation of Delaware

Application January 28, 1955, Serial No. 484,655

7 Claims. (Cl. 206—46)

This invention relates generally to mounting articles in a container and is particularly directed to a novel spacer member for resiliently positioning delicate or easily damaged articles in fixed spaced relation with the walls and bottom of a container.

One of the principal objects of the present invention is to provide spacer members particularly adapted for positioning articles, such as transformer elements, in centered spaced relation with the walls and bottom of a container.

Another object is to provide spacer members which will prevent vertical and lateral movement of the articles positioned in a container.

Another object of the present invention is to provide spacer members which will not deform or destroy the container walls and which are adaptable for use in containers of different sizes and shapes.

Another object is to provide spacer members for positioning delicate articles in a container so that shock or vibration on the container will not damage the articles.

Another object is to provide a novel shipping package wherein articles, such as transformer elements, may be removably positioned in spaced relation to the walls of a container by resilient spacer members, and the container filled with a fluid that will act as a preservative during shipping and may be used as a cooling medium during subsequent operation of the article.

Another object of the present invention is to provide simple, economic spacing means for mounting transformer parts or other articles in a container whereby the necessity for rigid securing means will be obviated.

These and other objects and advantages will become apparent hereinafter.

The invention is embodied in a resilient spacer member having an upper lip engageable with an article or article casing and a lower vertical abutment flange adapted for abutment against the casing with arcuate means interconnecting the lip and flange and extending outwardly for engagement with the walls of a container.

The invention also consists in the parts and in the arrangements of parts hereinafter described and claimed. In the accompanying drawings which form a part of this specification and wherein like numerals refer to like parts wherever they occur:

Fig. 1 is an exploded perspective view showing the preferred embodiment of the present invention.

Fig. 2 is a longitudinal sectional view showing the spacer members assembled on the casing and mounted in a container.

Fig. 3 is a transverse sectional view taken along line 3—3 of Fig. 2, and

Fig. 4 is a perspective view partly broken away showing a spacer member adapted for use with a smaller casing.

Referring to Fig. 1 of the drawings, it will be seen that the embodiment of the invention which has been shown is applied to a plate assembly or casing 10 especially adapted for enclosing and supporting a replacement trans-

2

former core and coil assembly (not shown), although the invention may be used with any type of article as will become apparent hereinafter.

The casing 10 for supporting the article comprises an upper plate 11 having opposite ends 12 and down-turned side flanges 13, and a lower plate 14 having opposite ends 15 and up-turned side flanges 16. The upper and lower plates 11 and 14 are connected together in fixed spaced relationship by supporting members or legs 17 to provide an opening or space in which an article may be secured. Each of the legs 17 may be formed from an angle bar to provide a surface abutment 18 and an edge abutment 18' adjacent to the ends 12 and 15 of the plates 11 and 14 respectively, the legs 17 being positioned in pairs so that the surface abutments 18 define the ends of the casing 10. Each of the legs 17 has a lower end 19 secured to the side flanges 16 of the lower plate 14 as at 20 in any suitable manner, and an upper end 21 secured to the side flanges 13 of the upper plate 11, as at 22. The upper end 21 of each of the legs 17 has an upper margin or edge 23 spaced vertically from the end 12 of the upper plate 11 to provide an opening or slot 24 which is defined horizontally by inside surfaces 25 on the side flanges 13 of the upper plate 11. The casing 10 is also provided with lifting tabs or flanges 26 secured to the upper plate 11 and having openings 27 therein for engagement by conventional lifting means (not shown) for inserting or removing the casing 10 from a conventional container 28 having inside walls 29 and a bottom 30, Figs. 2 and 3.

The invention is embodied in a centering and spacing means which comprises resilient spacer members 31, one which is assembled on each end of the casing 10 to provide the mounting assembly for positioning the article in the container 28. Inasmuch as each of the spacer members 31 is alike only one need be described in detail.

The spacer member 31 comprises an upper portion, a mid-portion and a lower portion, the upper portion including an upper lip or tab 32 having a free inner edge 33 and side margins or edges 34. The lip 32 is substantially horizontally positioned, but may slope slightly upwardly to its inner edge 33 so that the casing 10 will be in positive frictional engagement therewith, as will be described hereinafter. The lip 32 may have a cut 35 a predetermined distance from each of the side margins 34 to define outer auxiliary tabs or side lips 36. The outer edge of the lip 32 is formed into a vertically extending abutment 37 adapted to bear against the surface abutment 18 of the legs 17 when the spacer member 31 is assembled on the casing 10. The mid-portion of the spacer member 31 is formed integral with the abutment 37 and comprises a pair of elongated arcuate ribs 38, which are spaced to define an elongated central opening 39, the ribs 38 curving outwardly for engagement with the walls 29 of the container 28. The lower portion of the spacer member 31 is formed integral with the mid-portion and comprises an abutment flange or supporting lip 40 positioned substantially in the same vertical plane as the abutment 37 and having a lower end 41. A series of vertical cuts 42 may be formed in the spacer member 31 a predetermined distance from each side margin 43 of the spacer member 31 to define outer projections 44 and inner projections 45 having outer side edges 46 adapted to bear against the edge abutment 18' of the legs 17 when assembled on the casing 10. The projections 44 and 45 are formed at the juncture of the mid-portion and the lower portion and extend inwardly therefrom so that they protrude beyond the abutment flange 40, which is adapted for engagement on the surface abutments 18 adjacent to the lower end 19 of the legs 17.

When the resilient spacer members 31 are to be assembled on the casing 10 for insertion in the container 28, the horizontal lip 32 of one spacer member 31 is

positioned in the horizontal slot 24 at one end of the casing 10 so that the side margins 34 of the lip 32 are adjacent to the inside surfaces 25 of the opposed side flanges 13 thereby positioning the lip 32 between the end 12 of the upper plate 11 and the upper margins 23 of the legs 17 with the inner edge 33 of the lip 32 abutting the upper plate 11. Another spacer member 31 has its horizontal lip 32 similarly positioned in the slot 24 at the other end of the casing 10. When so positioned, the abutment 37 of each of the spacer members 31 is engaged on the surface abutments 18 at the upper ends 21 of the legs 17 at one end of the casing 10, and the abutment flanges 40 of each of the spacer members 31 is engaged on the lower ends 19 of the surface abutments 18. The outer projections 44 extend inwardly from the abutment flange 40 of each spacer member 31 between the legs 17 at each end of the casing 10 with the edges 46 bearing against the edge abutments 18' so that lateral movement of the lower end of the casing 10 relative to the spacer member 31 will be prevented when the mounting assembly is positioned in the container 28. It is now apparent that when the resilient spacer members 31 are assembled on the casing 10, the ribs 38 are bowed outwardly relative thereto and the mounting assembly is now conditioned for insertion into the container 28.

Upon the insertion of the mounting assembly in the container 28, the resilient ribs 38 of the spacer members 31, which normally curve outwardly a greater length than the distance between the inner walls 29 of the container 28, are deformed to assume the shape of the walls 29 and to conform to the distance therebetween so that complementary bearing surfaces are formed between the inner walls 29 and the ribs 38. Although the area of the ribs 38 is small enough to be easily deformed for bearing engagement against the walls 29 of the container 28, it is to be understood that the rib area is sufficient to prevent the rupture or deformation of the shape of the container walls 29, which might present problems in subsequently sealing the container 28.

As shown in Fig. 2, when the mounting assembly is inserted into the container 28 a wedging action results, which causes the ribs 38 to flatten out so that the spacer members 31 become elongated and the lower edge 41 of each of the abutment flanges 40 is moved downwardly beyond the lower plate 14. It is apparent that the wedging action between the ribs 38 and the walls 29 of the container causes the abutment flange 40 to slide downwardly on the surface abutments 18 and the projections 44 to slide downwardly on the edge abutments 18' of the legs 17. However, after the ribs 38 have assumed the shape of the container walls 29, no more relative vertical movement will take place between the casing 10 and the spacer member 31. Furthermore, as the abutment flange 40 is moved downwardly on the surface abutments 18, the frictional engagement therebetween will increase so that when the assembly is finally positioned in the container 28 no relative horizontal movement can take place.

As seen hereinbefore, lateral movement of the article casing 10 at its lower end is prevented by the engagement of the side edges 46 of the projections 44 on the edge abutments 18' of the casing legs 17. Lateral movement at the upper end of the casing 10 is prevented by the engagement of the side edges 34 of the lip 32 on the inside surfaces 25 of the side flanges 13. In addition, the weight of the articles encased and the frictional engagement of the resilient ribs 38 against the container walls 29 will prevent any vertical movement between the mounting assembly and the container 28.

When the mounting assembly has been positioned in the container 28, the article casing 10 will be automatically centered in spaced relationship with the inside walls 29 of the container and shock or vibration transmitted thereto will be absorbed by the resilient ribs 38 of the spacer members 31. Inasmuch as the lower edge 41 of

the abutment flange 40 extends below the casing 10, the lower edge 41 will be positioned against the bottom 30 of the container 28 thereby spacing the article casing 10 therefrom.

The spacer members 31 are adapted for use with different sizes of article casings and may be used with different sizes of containers. When it is desired to assemble the spacer members 31 on a smaller size casing 10, the outer tabs 36 are removed or turned upwardly so that the cuts 35 define the side margins of the lip 32, as shown in Fig. 4. The distance between the cuts 35 or the width of the lip 32 is predetermined for engagement in the horizontal slot 24 of the smaller casing. Similarly, by removing or depressing the outer projections 44 the inner projections 45 will engage the edge abutments 18' of the smaller casing. It is apparent that any number of paired projections 44 and tabs 36 may be provided for adapting the spacer member 31 for use with different sizes of casings. Furthermore, any type of article may be mounted in a container 28 by the spacer members 31 if coating surface and edge abutments and a lip-receiving slot are provided therefor.

This invention is intended to cover all changes and modifications of the example of the invention herein chosen for purposes of the disclosure, which do not constitute departures from the spirit and scope of the invention.

What we claim is:

1. A spacer member having upper and lower ends, said upper end defining the inner edge of a horizontally-extending tab having side edges spaced apart a predetermined distance, a pair of cuts formed inwardly of said side edges to form outer auxiliary tabs and a central tab having a predetermined width, a vertical abutment formed integral with the outer edge of said tab, spaced arcuate resilient ribs curving outwardly and downwardly from said vertical abutment, an abutment flange formed integral with said ribs and positioned in the same vertical plane as said abutment, said lower end of said spacer member defining the lower edge of said abutment flange, and a pair of spaced projections formed from said abutment flange and extending substantially normal therefrom, said projections having outer margins spaced apart a predetermined distance.

2. A spacer member having upper and lower ends, said upper end defining the inner edge of a horizontally-extending tab having side edges defining the width of said spacer member, a pair of cuts formed in said tab forming outer auxiliary tabs and a central tab having a predetermined width, a vertical abutment formed integral with the outer edge of said horizontally-extending tab and having side edges conterminous with the side edges thereof, spaced resilient ribs connected to said vertical abutment and having outer side edges conterminous with the side edges of said vertical abutment, an abutment flange connected to said resilient ribs positioned in the same vertical plane as said vertical abutment and having side edges conterminous with the side edges of said ribs, said lower end of said spacer member defining the lower edge of said abutment flange, and a series of cuts defining paired spaced projections formed substantially at the juncture of said resilient ribs and abutment flange, each of said projections having an outer edge spaced from a side edge of said abutment flange a predetermined distance.

3. A mounting assembly comprising an article casing having an upper plate, a lower plate spaced from said upper plate by a plurality of legs having abutment surfaces formed thereon, the upper end of said legs being spaced from said upper plate to define a horizontal slot at each end of said casing, and a resilient spacer member removably positioned on each end of said casing, said spacer member having an upper horizontal tab positioned in said horizontal slot, a vertical abutment formed on one end of said tab and engaged on said abutment sur-

faces of said legs adjacent to the upper ends thereof, spaced ribs formed on said abutment and downwardly curving therefrom, an abutment flange formed on said spaced ribs and positioned in abutting relationship with the portion of said abutment surface of said legs adjacent to the lower ends thereof, spaced projections formed on said abutment flange and inwardly extending relative thereto for engaging the vertical margins of said legs adjacent to said abutment surfaces thereon, said spaced ribs being adapted for frictional engagement with the 10 walls of a container when said mounting assembly is positioned therein.

4. A mounting assembly comprising an article casing having an upper plate, a lower plate spaced from said upper plate by a plurality of vertical legs having surface abutments defining the ends of said casing, the upper end of said legs being spaced from said upper plate to define horizontal slots at the ends of said casing, and a resilient spacer member removably positioned on each of the ends of said casing, said spacer member having an upper horizontal tab positioned in said horizontal slot, a vertical abutment formed on said horizontal tab and engaged on said surface abutments of said legs at the upper ends thereof, spaced ribs formed on said abutment and downwardly curving therefrom, an abutment flange formed on said spaced ribs and positioned in abutting relationship with the portion of said surface abutments of said legs adjacent to the lower ends thereof, and a plurality of projections formed on said abutment flange and inwardly extending relative thereto for engaging vertical margins of said legs adjacent to said surface abutments thereon.

5. In a container having side walls and a bottom for enclosing transformer elements, a casing for supporting the elements including upper and lower plates interconnected by end-defining supporting members having end surfaces and opposed margins, and centering and retaining means comprising a pair of spacer members assembled on opposite ends of said casing, each of said spacer members having resilient ribs frictionally engaging the side walls of said container and spacing said casing therefrom, a lower abutment connected to said ribs and positioned on the bottom of said container to space the lower plate of said casing therefrom, said lower abutment having a portion in frictional contact with said casing end surfaces and spaced projections positioned between said opposed margins, and a supporting tab connected to said ribs and engageable with the upper plate of said casing.

6. A spacer member for mounting an article casing 50 in spaced relation with the walls and bottom of a container, said spacer member comprising upper, intermediate and lower portions, said upper portion including a horizontally-extending flange having a pair of laterally spaced cuts forming a central tab of predetermined 55 width and side tabs which with the central tab have a

predetermined overall width, and an upper vertical abutment extending downwardly from said horizontal flange; said intermediate portion including a resilient arcuate rib extending outwardly and downwardly from said upper abutment, said rib having an outer surface adapted to frictionally contact a container wall; said lower portion including a lower vertical abutment connected to the lower end of said rib and positioned in substantially the same vertical plane as said upper abutment, a first pair of projections extending horizontally from said lower vertical abutment and having outer side margins spaced apart a predetermined distance, and a second pair of laterally spaced projections extending horizontally from said lower vertical abutment and having outer side margins spaced apart a predetermined distance, said second pair of projections being positioned between said first pair of projections.

7. In a transformer element shipping construction including a container having side walls and a bottom, a casing for supporting transformer elements, said casing comprising an upper and lower plate positioned in fixed vertically spaced relation by end pairs of supporting members having end surfaces and opposed margins, the upper ends of said end surfaces being spaced below 20 said upper plate; and centering and retaining means for mounting said casing in spaced relation with the side walls and bottom of said container, said centering and retaining means comprising a pair of spacer members positioned on the end pairs of supporting members of 25 said casing, each of said spacer members having a resilient rib extending outwardly from said casing in frictional contact with said container, upper and lower abutments formed integral with said rib and in frictional surface contact with the end surfaces of said supporting members 30 of said casing, said lower abutment extending below said lower plate of said casing and having a free edge positioned on the bottom of said casing, a supporting lip formed integral with said upper abutment and extending under the upper plate of said casing through the 35 space between the upper ends of said supporting member end surfaces and said upper plate, and a pair of projections extending from said lower abutment and having outer side margins spaced apart a predetermined distance, said side margins being received between said 40 opposed margins of said supporting members.
